COKE OVEN APPARATUS

Joseph Becker, Pittsburgh, Pa., assignor to Koppers Company, Pittsburgh, Pa., a corporation of Delaware

Application November 10, 1939, Serial No. 303,722

3 Claims. (Cl. 214—18)

The present invention relates to horizontal coke ovens more especially of the regenerative type and particularly contemplates improvements in the disposition of their coke-side equipment for manipulating the oven doors, the coke guide, and the like, that provide enhanced protection to the structural integrity of a battery of such ovens and will at the same time be very economical of that space along the battery-face which is required to accommodate such equipment.

In prior practice in coke ovens of the stated class, the door machine, the coke guide and other heavy equipment commonly employed in operative attendance at the coke-side of a battery have been propelled along that battery-face on trackage that is mounted on a bench supported by the battery buckstays at a level adjacent to and just beneath the oven-soles. Such operating-bench of a battery is necessarily of great weight for it must be of a construction sufficiently rugged to support not only the door-handling machine, the coke guide, and frequently other equipment as well, but it must at periodic intervals be also adapted to support the massive coke-oven doors themselves as they are moved along the bench during their removal from and return to operating position in the coking-chamber mouths. All this accumulation of load has had to be borne by the buckstays that supported the operating bench.

The primary function of the buckstays in a coke-oven battery is however to assist in the support and retention, in their designed arrangement, of the brickwork comprising its masonry. To effect this end, the buckstays are placed at both ends of the oven heating-walls in pressure contact with the masonry comprising their jamb-ends, the upper ends of buckstays at opposite ends of a heating wall being joined together by tie-rods that extend over the top of the battery. At the juncture between said tie-rods and buckstays there is commonly provided resilient means adapted to permit a certain amount of elastic play between the latter and the heating walls so as to permit minor fluctuations in the proportions of the heating wall inside its confining buckstays without greatly altering the pressure of their contacts.

In those prior designs wherein the great load both of the operating bench and of the thereon-supported operating machinery has been carried by the battery buckstays, the latter have been seriously hampered in the performance of the above-described primary function because

5 slight distortions as well as the vibrations of the bench, resulting from the propelling therealong of the above-stated heavy operating equipment, are all transmitted directly to said buckstays to subject them to slight but substantially continuous movement against the masonry of the heating-wall jambs or the intermediate face-plates. Eventually, there unavoidably results a permanent distortion from which the said resilient means are unable to return the buckstays to their original continuity of pressure-contact against the heating-wall jamb faces. Small interstices are thus created between the jamb-ends of the heating-wall masonry and the face-plates 10 15 that cover them, into which gases, vapors and carbon from the coking chamber can penetrate leaving deposits which, unless preventive measures are taken, can make any buckstay-distortion permanent and even increase it to proportions such that drastic corrective steps must be taken. Ultimately the brickwork of an oven wall follows the bowing of its associated buckstays thereby causing serious damage to its costly masonry and finally requiring its removal from operation for extensive repairs.

20 These circumstances and eventualities are confirmed by the fact that buckstays on the coke-side of a battery, in which location they normally support the heavy door-machine and the like, require straightening or replacement about three times as frequently as those at the machine-side (i. e., the pusher-machine side), of the battery where such operating equipment is usually supported on the pusher machine with 25 the result that neither it nor the oven doors are ever carried by the machine-side bench or buckstays.

30 In U. S. Patent No. 1,411,262 which issued April 4, 1922, the present inventor disclosed an improved design of machine for handling that apparatus which is moved along the battery face in the course of oven operations. Structurally, the body member of the therein disclosed machine was formed in the shape of an inverted letter L whose free ends were provided with wheels or rollers whereby it could be propelled along the battery front. The longer, vertically-disposed leg of said body member was supported by wheels whereby it was propellable along a 35 single track located at yard level out of contact with the battery structure, and the shorter, horizontally-disposed leg was arranged by means of a roller to engage a track affixed to the upper ends of the buckstays. By means of such apparatus, the actual door-handling mechanism,

the coke guide, and the like, were all supported on the said L-shaped body member out of contact with the battery bench and, in consequence, of its contribution to the coking art, it became possible for designers to reduce the direct load on the buckstays and in addition to substitute a light foot-bench for the previously employed heavy, expensive one. Even through the improved design of said patent greatly decreased the load necessarily supported by the buckstays of a coke-oven battery such load was however not entirely eliminated because this said newer apparatus was propped upright against the face of the battery in such manner that the buckstays were still subjected to much of the vibrations and jarring that resulted from the travel of the apparatus along the battery face.

One of the principal objects of the present invention is therefore the provision more especially for the coke-side of a coke-oven battery of a machine that is adapted to support the door-handling mechanism, the coke guide, and the like, closely adjacent the mouths of the coking chambers and independently of all features of the battery-structure so that its masonry and buckstays need no longer be subjected to the jarring and stresses and strains created by propelling such equipment on means either entirely or in part supported by the buckstays.

Another object of invention is the provision of a device that will fulfil the above-stated requirements and will require only a relatively narrow space along the battery face for its successful utilization.

A further object of invention is to provide apparatus for the stated purpose that will permit retention of the quencher-car in its usual position adjacent the front of the battery, or its trackage to be moved even closer to the buckstays thereby to decrease the distance the incandescent coke-cake must be pushed before it falls into the quencher-car.

A further object of improvement is to provide a propellable support, more especially for the oven-operating mechanisms employed at the coke-side of a battery, that is of a design making feasible a complete elimination of the operating-benches, thereby relieving the buckstays of such additional weight.

The invention has for further objects such other improvements and such other operative advantages or results as may be found to obtain in the processes or apparatus hereinafter described or claimed.

According to the present invention the various mechanical features employed for handling coke-oven doors, for directing hot coke into the quencher-car and for general attendance to the required oven-operations at the face of an oven battery are mounted on a gantry that is propellable along the battery-front on trackage located substantially at yard level and out of contact with the structural mass of the battery, the legs of said gantry being disposed on opposite sides of the quencher-car trackage with the bridge section thereof at sufficient height above the top of said car to permit its free passage therebeneath. The gantry of the invention is adapted for employment in combination with a battery having the commonly-used operating-bench but it is especially advantageous when used in association with a benchless battery because with such structure it becomes possible to station closer to the mouths of the coking chambers, that leg of the gantry which more

5 directly supports the said battery-operating mechanisms, thereby correspondingly to reduce the necessary span of the gantry. A small platform supported at a convenient level on the gantry of invention can of course serve as adequate substitution for the extended operating bench of the prior art.

In the accompanying drawings forming a part 10 of this specification and showing for purposes of exemplification a preferred apparatus in which the invention may be embodied and practised but without limiting the claimed invention specifically to such illustrative instance or instances:

15 Fig. 1 is a vertical sectional view taken cross-wise of a regenerative coke-oven battery through a coking chamber thereof and showing such accessory equipment as the larry-car, the pusher machine, and the like customarily employed in the operation of such ovens and also an embodiment 20 of the gantry coke-oven bench of the present invention positioned at the coke-side of the illustrated battery, said gantry having mounted thereon a door-handling mechanism, a coke-guide, and a leveler-bar for leveling the oven charges from the coke-side;

25 Fig. 2 is a plan view of Fig. 1 with the larry-car omitted;

30 Fig. 3 is a section taken substantially along the line A—A of Fig. 6;

35 Fig. 4 is a section taken substantially along the line B—B of Fig. 6;

40 Fig. 5 is a section taken substantially along the line C—C of Fig. 6;

45 Fig. 6 is a view taken substantially along the line VI—VI of Fig. 1; and

Fig. 7 shows, on a scale somewhat altered from that used in the other drawings, the gantry of the invention in operating position at the coke-side of an oven in an underjet battery that is furnished with weather protection over the usual alley-way in which such devices as the reversing mechanisms are located.

Referring now to the drawings:

For the purpose of demonstrating the improvement of the present invention and the constructional and operative advantages resulting from its employment in combination with a coke-oven battery, there is shown in the accompanying drawings a diagrammatically represented coke-oven battery of the cross-regenerative type comprising many of the characteristic features of such a battery and some of the accessory equipment commonly used in its operation. The illustrated coke-oven battery comprises essentially a plurality of coking chambers 10 that extend crosswise of the battery and are disposed lengthwise thereof in alternation with flued heating walls 11. The flued heating walls are formed of brickwork whose masonry terminates at either 55 battery-face in jambs against which there abuts in pressure-contact the vertically-extending buckstays 12 which function to maintain the alignment of the heating walls as well as the brickwork thereof and the regenerator walls 13 in their designed positions in the heated battery. To effect this end the buckstays are each secured at their lower ends to the battery-supporting mat 14 and at their upper ends are joined to a 60 similarly-positioned buckstay at the opposite battery-face by tie-rod means 15 that extend across the top of the battery. Resilient means, such as coil-spring 16, are provided at each end 65 of the said tie-rods at their juncture with the buckstays thereby to provide for a certain 70 75

amount of movement, at that point, whereby a limited expansion and contraction of the included heating wall can occur without seriously altering the extent of the pressure-contact existing between it and said buckstays.

Beneath the heating walls and extending crosswise of the battery in substantial parallelism therewith are cross-regenerators 17 for preheating combustion media before introducing the same into the lower parts of the heating flues individually through ducts 18. Coking chambers 10 are closed at each end by removable doors 19, each such door comprising an external metal framework 20 and a thereby supported heavy refractory plug 21 that operates to prevent overheating of the metallic framework. The doors for the coking chambers are provided at both the coke-side and the machine-side of the battery with chock-doors 22 so that coal charged into the ovens from larry-car 23 through charging-holes 24 can be levelled from both sides of the battery.

At the end of the carbonization period, the residue of coke in the coking chamber is pushed therefrom by the usual pusher machine which is moved along the machine-side of the battery from oven to oven on trackage 25, as shown in Fig. 1. The said pusher machine comprises heavy framework 28 that supports the diagrammatically illustrated pusher-ram 26 and leveler-bar 27 and the both of which are provided with individual reciprocatory movement lengthwise of the coking chamber by means not shown, the former serving to remove the residual coke-cakes from the coking chambers whereas the latter operates to provide the top of coal freshly charged into an oven with a level surface such that the finished coke-cake will have no irregularities protruding above the upper edge of the coking-chamber mouth. Although for purposes of convenience it is not illustrated in the drawings, apparatus for operating the door-latches and manipulating the machine-side doors are also normally supported on the pusher machine.

According to the present invention, that heavy equipment customarily employed at the coke-side of a battery during routine oven operations is assembled on a gantry to form a unitary machine that is propellable from oven to oven on trackage located substantially at yard level, said machine and its supported equipment being entirely out of contact with any of the battery's structural features. The unitary machine of the invention also supports a short bench or deck, provided for the attendant's convenience during the cleaning of the oven doors and for such other duties as require a station adjacent the mouths of the coking chambers, thereby advantageously relieving the buckstays of the weight of such feature and reducing the material requirements therefor to a fraction of that previously required where it was stationary at the battery-face and was used to support divers oven-operating mechanisms.

As is clearly evident in the drawings the improved coke-side machine 30 of invention comprises as its principal structural element a framework in the form of a gantry having legs 31 and a bridge-section 32. The legs of said gantry are mounted on several flanged wheels 33 that are adapted to engage tracks 34, and at least one wheel on either side of the gantry has attached thereto a gear 35 whereby the improved unitary machine is propelled by means of an electrical motor 36 that is preferably individual

to each such driven wheel. Power is delivered from said motors to the gears 35 through an assembly of gears comprising pinion 37, idler gear 38, and intermediate gear 38-a, the motors being arranged by suitable wiring for individual control by the operator from cab 39.

Each bridge-section 32 is of sufficient span and height to permit free passage of coke quencher-car 40 therebeneath along its tracks 41. The bridge-sections of the gantry and the mechanisms that they support are protected against radiation from the incandescent coke contained in the quencher-car by means of an appropriate layer of insulation 42. Discharge gate 43 of the quencher-car permits loading of quenched coke on the coke-wharf 44.

Disposed on the gantry coke-side machine 30 and transportable thereby from coking chamber to coking chamber are a door-handling mechanism, a coke-side leveler-bar, and also a coke-guide that is arranged to direct and transport the hot coke-cake, as it emerges from its coking chamber under pressure exerted by the above-mentioned pusher-ram on the machine side, into the quencher-car therefor whence it is taken to a quenching station and cooled before being unloaded onto the coke-wharf. Looking along the coke-side of the battery of Fig. 1, there is observed in succession the door-handling mechanism 45, the leveler-bar 46, and the coke guide 47 all supported at the top of the gantry. Each of these oven-operating devices is arranged with individual actuating means controllable from cab 39.

The door-lifting mechanism, shown in enlarged view in Figs. 3 and 6, comprises a ram 48 that is reciprocable longitudinally of the coking chambers between four pairs of flanged wheels 49, each such pair being mounted for rotation on shafts 50 that are themselves carried by the vertically-disposed supports 51. At the forward end of the ram 48 is the ram-head 52 that is provided with reciprocal motion at right angles to the body of the ram along a line controlled by guide-ways 53. The said ram-head directly supports the divers mechanisms employed for manipulating the doors and for operating their latches, said mechanisms comprising respectively the door-hook 54, that is susceptible of actuation in a vertical plane so as to engage and release hook-plate 55 whereby the oven-doors are supported as they are moved by the reciprocal movement of the ram 48 between the positions indicated by the solid and dotted lines of Fig. 3, and the upper and lower latch-operating devices 56 that are constructed according to that design for such mechanism set forth in the co-pending application S. N. 140,960 of Berg and Crist, filed May 5, 1937 now Patent No. 2,179,608.

As shown in Fig. 4, the gantry of the invention is furnished with a leveler-bar 46 so that coal freshly charged into the coking chambers can be optionally levelled either solely from the machine-side or the coke-side or from both said sides of the battery either simultaneously or at spaced intervals. It is supported on the gantry by means similar to that previously described for the support of the door-ram; that is, the leveler-bar is held between spaced and paired pairs of flanged wheels 60 that are rotatable on upper and lower surfaces of said bar, substantially as illustrated, the said pairs of wheels being each supported on a shaft 61 therefor that is carried by an upright 62. The leveler-bar is

provided with reciprocating motion longitudinally of the coking chambers so that by opening chock-hole 57 of the coke-side doors it can be moved along a path extending into the gas-collecting space 58 of the coking chambers, said reciprocating motion being imparted thereto by motor 63 that operates through speed-reducing gearing 64 to rotate drum 65 around which cables 66, 67, are wound in opposite directions, the said cables being attached to the leveler-bar adjacent respectively its inner and outer ends after passing respectively over sheaves 68, 69. Rotation of drum 65 in opposite directions will thus cause similar travel of the leveler-bar between the flanged wheels 60.

The coke-guide 41 is disposed on the gantry of the invention on the opposite side of the leveler-bar from that at which the door-handling mechanism is located. It is made up in the present instance, as shown in Figs. 5 and 6, of two rows of vertically-spaced, horizontally-extending metallic slats 70 that are supported on the inner side of a framework formed by the vertical H-beams 71, the horizontal channel-bars 72, 73, and the angle-irons 74 that are arranged substantially as shown in said figures. Attached to the bottom of the framework are the heavy plates 75, 76, that are formed of a metal suitable for resisting the abrasive effect of the hot coke as it is pushed over their surfaces. The said framework of the coke-guide is also mounted on the gantry for reciprocating movement longitudinally of the coking chambers. To facilitate such movement its lower part rests on pairs of wheels 77 and between the flanges thereof, each such pair being supported on a rotatable shaft 78 that extends through the bushing-block 79 carried by I-beams 80, and the top of said framework is arranged to move between and be supported by spaced rollers 81 that depend from channel-bars 82. Actuation of the coke-guide is effected by motor 83 operating through the speed-reducing gearing 84 and the pinion gear 85 that is disposed for engagement with rack 86 located on the bottom of the framework of the coke-guide. Pinion gear 85 is also supported on bushing-block 79. The actuating mechanism for the coke-guide is preferably so arranged that, at its limit of travel toward the battery, there remains a small clearance between the slats of said guide and the jamb-plates surrounding the oven-mouth, so that vibrations of the former created by the passage of pushed coke therethrough are not directly transmitted to the battery structure. To this end, the divers features of the coke-guide are formed of structural materials that are sufficiently rugged independently to support the pushed coke without their distortion.

Projecting outward from the face of the battery at a level just beneath each of the oven-soles is a small shield-plate 87 that serves to carry the small amount of such detritus as breeze and the like, loosened from the coke-cake during its pushing, across the gas- and the air-flow reversing mechanisms, respectively 88, 89, into a receptacle 90 therefor on the gantry whence it can be intermittently removed to the quencher-car. The said shield-plates thus serve to protect the combustion-media flow-reversing mechanisms from becoming fouled with fine coke and to maintain the pavement of alley 91 along the battery-front in orderly condition.

According to the present improvement those benches usually supplied at the face of the battery for the convenience of the operators during

the oven-pushing operations, are located on the gantry of the invention. In the present instance there are two such members, a lower one 92 that is located a short distance below the oven-soles 5 and an upper one 93 that has projecting therefrom small stages which give easy access to the tops of the doors for cleaning their sealing edges. A stairway 94 connects said lower and upper benches.

- 10 At the end of the battery and supported adjacent the outer surface of a pinion wall thereof is a bench 95 having a stairway 96 that reaches to yard level. The said bench 95 is preferably at a level adjacent that of the operating platform 15 92 of the gantry thereby serving as a convenient means of access to the latter.

In Fig. 7, the gantry of the invention is shown in combination with a coke-oven battery of the underjet type having, adjacent the lower part of 20 the battery-face, a weather protection formed by the vertically- and horizontally-disposed members, respectively 97, 98, which are arranged to form substantially continuous surfaces along the face of the battery and are adapted to serve, more 25 especially in those latitudes having uncommonly heavy falls of rain or snow, as means of protection for the battery-basement and from operating interruptions of those devices usually employed for regulating the flow of combustion 30 media into and out of the battery. The said members 97, 98, are preferably formed of light construction such, for example, as metallic sheets or thin concrete slabs. The horizontal surface 35 98 can, of course, be employed as a sort of catwalk but, being of relatively light construction and having no trackage therealong nor heavy operating equipment to cause vibrations thereof, its load on the buckstays is not of any considerable consequence.

From the foregoing it will be manifest that by means of the gantry of the invention the heavy mechanisms normally required more especially at the coke-side of a battery of horizontal coke ovens, can be stably supported in their required 40 positions closely adjacent to the battery-face yet entirely out of contact with structural elements thereof while still retaining the quencher-car in its normal position in respect of the battery. By means of the gantry it becomes also feasible to dispense with the extended battery-supported operating bench of the prior art and the large requirements of material for its construction. In consequence of its great stability, the gantry construction makes it feasible to employ a leveler-bar 45 of effective length at the coke-side of the battery.

It has heretofore been general practice to level the coal-charges of a battery of horizontal coke ovens entirely from the one battery-face; that is, from the pusher machine-side. In consequence of the relatively considerable length of modern coke ovens and of their large quantities of to-be-levelled coal and also of the high temperatures in the adjacent oven brickwork, this practice has severely taxed the leveler-bar for which the provision of a material that is able successfully to cope with the said operating conditions and to pass through a charged oven along a strictly horizontal course, without bending at its far end, is more a wish than a reality. The affects of any 50 sagging or bending of the leveler-bar as well as its whipping action during movement are all most pronounced in those parts of the coal charge remotest from the leveler-bar support. In coke ovens having considerable length of coking chamber, the levelled coal-charge has thus tended to

exhibit a locally higher bulk density adjacent the coke-side than obtained at the machine-side of the battery, thereby still further increasing that normal discrepancy of heat requirements between a coke-side and a pusher machine-side heating-wall area resulting from the tapering of the coking chambers. In so far as there is concerned only the simple supplying of the added coking heat required by these zones of coal having a higher bulk density, the situation can of course be simply accommodated by increasing the amount of fuel gas burned in those heating flues thereadjacent and, in those cases where the employed coals exhibit only contraction throughout the coking process, these circumstances offer no insurmountable disadvantages.

When, however, the charged coals are somewhat expanding or belong to those borderline groups exhibiting neither considerable expansion nor contraction during their coking, the presence or absence of such localized zones of higher bulk density in the levelled charge can be the difference between a damaged or undamaged wall or between a relatively difficultly or easily pushed charge, and a brief consideration, at this point, of the situations created by their presence, more especially at the coke-side of an oven, may not be amiss in clarification of the difficulties they engender.

Due to the tapering of the coking chambers, the heating flues at the coke-side of an oven are of lesser cross-section than those at the machine-side and since the quantity of to-be-coked coal adjacent the former is always the larger, there is naturally required, for the bringing of the whole of an oven-charge simultaneously to the same degree of coking, higher temperatures in the coke-side flues so that coking heat can be flowed faster into the adjacent coal. If, in addition, the coal at the coke-side has a higher bulk density than at the opposite oven-end, the difference in temperatures between the coke-side and the machine-side flues must therefore be still further increased in compensation. Now, one of the interesting characteristics of expanding coals is that many of them can be coked at lower temperatures and at slower rates of coking without their exhibiting a serious degree of expansion but, if their critical temperatures and rates-of-heating are exceeded, they expand with the exertion of considerable force. In modern coke ovens that are especially designed for operating at faster coking times there can thus be observed the phenomenon of a coke-oven charge that has expanded at the coke-side sufficiently to cause "stickers" or even to damage the heating wall whereas at the machine-side it has produced no untoward situation.

From the above given, it becomes apparent that the increase of bulk density of the coke-side portion of a coke-oven charge, caused by its compression in that region through a sagging leveler-bar, can be the added influence causing damage to heating walls that would otherwise retain their integrity, and it is further apparent that, if compression of the levelled charge is unavoidable, it is advantageous that such condition should rather exist at the oven's machine-side and also that means for reducing the extremes to which bulk density is altered in any portion of the charge during the levelling operation will supply a needed contribution to the coking art.

The advantage of having the region of higher bulk density at the machine-side of an oven-charge does not reside exclusively in the increased

protection provided to the walls but also in the advantage it furnishes in the pushing of the coked charge. For example, if the freshly charged coal has been levelled exclusively from the machine-side and its region of greatest bulk density is adjacent the coke-side of the oven there can exist in the finished coke-cake a zone of coke that is in pressure-contact with the oven walls at that side of the battery. This means that the pushing-pressure of the ram must be transmitted through a large part of the coke-cake which is substantially free of the oven walls, and that, in consequence, a major portion of the entire cake can be collapsed upon itself inside the oven without starting the plugged portion, and the entire cake will have to be dug out. When such circumstance arises, the pressure of the ram is transmitted to the oven walls and they are not adapted to resist such force. They should act only as a sort of coke-guide during the pushing operations. If, however, the densest part of the coal-charge is shifted from the coke-side to the machine-side of the oven by levelling exclusively from the former side of the battery, that portion of the resulting coke-cake with the greater tendency to wedge between the oven walls is located adjacent heating flues having lower temperatures and also more closely adjacent the pusher-ram itself so that the pressure exerted by the latter more nearly directly bears on the possibly wedged portion and, in the event, there results a collapse of any intermediate coke in attempting the starting of the coke-cake, it will be restricted to a relatively minor portion thereof and leave the more substantial part of the oven-charge intact for normal pushing.

The gantry of the instant improvement now makes it feasible to employ a full-length leveler-bar at both the machine-side and the coke-side of a battery of horizontal coke ovens thereby providing means whereby those portions of greatest compression of the coal-charge, caused by the tendency of the leveler-bar to sag during the levelling operation, can be optionally disposed lengthwise of an oven in accordance with the coking characteristics exhibited by a coal or its mixture at the employed flue-temperatures and rates of coking. Other factors being equal, the zones of greatest bulk density of oven-charge can be placed at the one side of the battery by levelling exclusively from its opposite side and if preferred such zones will tend to be positioned in the middle of the oven when each oven-half is levelled solely by the bar adjacent thereto. The last-mentioned method of course tends to effect the least change of bulk density in any portion of the charge and is of special advantage in use with coals having a tendency to expand during the coking process because the average sagging of the both leveler-bars will be the least.

Those features of invention exemplified in the foregoing description which relate to "Coke-oven method," are made the subject-matter of my co-pending divisional application for Letters Patent of the United States, filed January 7, 1943, Serial No. 471,630.

The invention as hereinabove set forth is embodied in particular form and manner but may be variously embodied within the scope of the claims hereinafter made.

I claim:

1. The arrangement of the coke-side equipment for a battery of regenerative horizontal coke ovens which comprises: a battery of hori-

horizontal coke ovens arranged side-by-side in a row; quencher car tracks extending alongside the coke-side battery front; a gantry propellable alongside the coke-side battery-front on ground-rails out of contact with the battery with the legs of the gantry disposed on tracks on opposite sides of the quencher car tracks and its bridge section at a height to permit free passage of a quencher car therebeneath; the coke-side battery-operating mechanisms for handling the oven doors and guiding hot coke to the quencher car being mounted on the gantry for overhanging movement away from the leg of the gantry next to the battery to the mouths of the oven chambers and back again; said battery-operating mechanism being more directly supported on the gantry over its leg closet to the coke-side battery front and said coke-side battery front being benchless, that is, not having the conventional bench fixed to the coke-side battery front at an elevation for travel therealong from oven to oven, the aforesaid coke-side battery operating mechanisms for handling the oven doors and guiding hot coke to a quenching car on the quencher car tracks; and said gantry having its leg which more directly supports the aforesaid battery-operating mechanisms stationed closer to the mouths of the coking chambers inside that line to which the outer extremity of such a bench would project, to reduce the distance of the aforesaid overhang and thus reduce the span of the gantry to that for mere clearance of the opposite sides of the quencher car on its tracks.

2. The arrangement of the coke-side equipment for a battery of regenerative horizontal coke ovens which comprises: a battery of horizontal coke ovens arranged side-by-side in a row; quencher car tracks extending alongside the coke-side battery-front; a gantry propellable alongside the coke-side battery-front on ground-rails out of contact with the battery with the legs of the gantry disposed on tracks on opposite sides of the quencher car tracks and its bridge section at a height to permit free passage of a quencher car therebeneath; the coke-side battery-operating mechanisms for handling the oven doors and guiding hot coke to the quencher car being mounted on the gantry for overhanging move-

ment away from the leg of the gantry next to the battery to the mouths of the oven chambers and back again; said battery-operating mechanism being more directly supported on the gantry over its leg closet to the coke-side battery front and said coke-side battery front being benchless, that is, not having the conventional bench fixed to the coke-side battery front at an elevation for travel therealong from oven to oven, the aforesaid coke-side battery operating mechanisms for handling the oven doors and guiding hot coke to a quenching car on the quencher car tracks; and said gantry having its leg which more directly supports the aforesaid battery-operating mechanisms stationed closer to the mouths of the coking chambers inside that line to which the outer extremity of such a bench would project, to reduce the distance of the aforesaid overhang and thus reduce the span of the gantry to that for mere clearance of the opposite sides of the quencher car on its tracks; and an oven coal-charge leveler-bar carried by the gantry for movement therewith from oven to oven, and mounted on the gantry for reciprocal movement over its bridge section, transversely of the line of movement of the gantry, into and out of the oven chambers through their coke-side doors at the tops thereof.

3. The arrangement of the coke-side equipment for a battery of regenerative horizontal tapered coke ovens which comprises: a gantry propellable alongside the coke-side battery front on ground-rails with the legs of the gantry disposed on tracks on opposite sides of quencher car tracks and its bridge section at a height to permit free passage of a quencher car therebeneath; an oven coal-charge leveler-bar carried by the gantry for movement therewith from oven to oven, means mounted on the gantry for causing reciprocal movement of said leveler-bar over its bridge section, transversely of the line of movement of the gantry, into and out of the oven chambers through their coke-side doors at the tops thereof and guide means mounted on the gantry, supporting the leveler-bar for free suspended movement into and out of the oven chambers.

JOSEPH BECKER.
